VASE

Zachary P. Abuza, 19425 Van Aken 44122, and Stanley W. Morgenstern, 2887 Broxton 44120, both of Shaker Heights, Ohio

Filed Jan. 25, 1971, Ser. No. 109,738

Term of patent 14 years

Int. Cl. D11—02

U.S. Cl. D29—28

FIG.1

FIG.2

FIG.3

FIG.4

FIG. 5

FIG.6

FIG. 1 is a top plan view of a vase showing our new design;

FIG. 2 is a side elevational view of the vase, the side opposite being identical thereto;

FIG. 3 is a bottom plan view thereof, the decorative motif being continuous about the vase with portions being broken away for convenience of illustration;

FIG. 4 is a top plan view of the lower section of the vase as used independently when the upper section is removed;

FIG. 5 is a side elevational view of the lower section of the vase as used independently when the upper section is removed; and

FIG. 6 is a fragmentary side elevational view of the upper section of the vase when removed from the lower section.

We claim:

The ornamental design for a vase, as shown and described.
